UNITED STATES PATENT OFFICE.

VERNE LAWRENCE HOLMES, OF LOS ANGELES, CALIFORNIA.

BED CONSTRUCTION.

Application filed January 17, 1924. Serial No. 636,705.

To all whom it may concern:

Be it known that I, VERNE LAWRENCE HOLMES, a citizen of the United States, and resident of Los Angeles, in the county of Los Angeles, State of California, have invented a new and useful Improvement in a Bed Construction, of which the following is a specification.

This invention relates to a bed and pertains particularly to a folding bed of the portable type. The present invention relates more particularly to a bed having a carriage forming the head end of the bed and supporting a bed frame which may be swung into horizontal or sleeping position or into vertical or collapsed position. Beds of the character described commonly have the frame pivotally attached to the carriage. The users of such beds often push the bed, when in open position, about the room with the result sometimes of collapsing the head upon the frame. This may be prevented by providing several well spaced points of supports for the carriage thereby providing great stability. The provision of stationary supports so spaced detracts from the compactness of the bed when collapsed.

It is an object of this invention to provide an additional support for the carriage which is moved into position to stabilize the latter when the frame is open and withdrawn when the frame is collapsed. Another object of this invention is to provide details of structure, whereby the additional support is automatically moved into position by the opening and closing of the bed frame.

These objects together with other objects and corresponding accomplishments are obtained by means of the embodiment of my invention illustrated in the accompanying drawings, in which:

At Fig. 1 is a perspective view of a fragment of the bed, parts being broken out to better illustrate the invention; Fig. 2 is a section as seen on the line 2-2 of Fig. 1; Fig. 3 is a section as seen on the line 3-3 of Fig. 2; and Fig. 4 is a section taken on the line 4-4 of Fig. 2 on an enlarged scale.

Referring more particularly to Fig. 1, the bed carriage is indicated by A. Pivotally mounted thereon is the bed frame B, and C indicates generally the stabilizing support.

The carriage has a base frame formed of side bars 5 and 5' connected by cross bars 6

and 7. The base is mounted upon casters 8 to provide easy means for moving the bed about. Mounted upon the base is the usual head 9. At the sides of the base are brackets 10 and 10' having bearings formed therein 60 in which are journalled trunnions extending from the sides of the bed frame.

The bed frame consists of side bars 11 and 11' joined at the head end by a cross bar 12 which may form a counterweight for the 65 bed frame. The usual bed spring is mounted upon the frame. Fixed to the frame at the head end is an auxiliary head 13. Springs 14 and 14' act as counterbalances for the frame. 70

Connected to cross bars 6 and 7 is a bar 15, and pivotally secured thereto at 16 is a stabilizer leg 17. A tension spring 18 tends to hold the leg 17 in open position. Mounted upon the leg 17 is a stop 19 to limit the 75 opening position of the leg. Mounted upon a bracket on the leg 17 is a roller 20 forming an offset abutment arranged to be engaged by the bar 12 on the bed frame. Disposed upon the end of the leg 17 is a caster 21 forming a foot. 80

When the bed is opened, that is, the frame B is in horizontal position, the leg 17 of the stabilizer will be in the position shown in dotted lines in Fig. 3. The spring 18 will 85 maintain the stabilizer leg in this position. It is obvious that an additional point of support well spaced from the bottom of the carriage is provided. This leg would detract from the compactness of the bed when 90 folded, unless retracted. Retraction is accomplished automatically, because upon raising the bed frame to vertical position, bar 12 engages the roller 20 and will swing the leg 17 against the action of spring 18 into 95 the position shown in full lines in Fig. 3.

What I claim is:

1. In a folding bed having a carriage and a bed frame pivotally secured thereto, a horizontal stabilizing leg pivoted intermediate its ends on said carriage, said leg having a supporting foot at one end and an offset abutment at the other end, said abutment being disposed to be engaged by said bed frame on raising the latter and to retract 100 said leg, and means tending to project said leg into supporting position. 105

2. In a folding bed having a carriage and a bed frame pivotally secured thereto, a horizontal stabilizing leg pivoted interme- 110

diate its ends on said carriage, said leg having an offset upstanding roller at one end and a supporting foot at the other end, said roller being disposed to be engaged by a cross bar at the head of said frame on raising the latter so as to retract said leg upon raising of said frame, and spring means

tending to project said leg into supporting position.

In witness that I claim the foregoing I 10 have hereunto subscribed my name this 11th day of January, 1924.

VERNE LAWRENCE HOLMES.
